UNITED STATES PATENT OFFICE.

ALPHONSE M. LEONI, OF BROOKLYN, AND ALBERT F. SCHREINER, OF LONG ISLAND CITY, NEW YORK, ASSIGNORS TO SAID ALPHONSE M. LEONI.

SEWAGE-SCREENING APPARATUS.

1,190,920.

Specification of Letters Patent. Patented July 11, 1916.

Application filed February 1, 1913. Serial No. 745,639.

To all whom it may concern:

Be it known that we, ALPHONSE M. LEONI, a subject of the King of Italy, and ALBERT F. SCHREINER, a citizen of the United States, residing, respectively, at Brooklyn, New York, and Long Island City, New York, have invented certain new and useful Improvements in Sewage-Screening Apparatus, of which the following is a clear, full, 10 and exact description.

This invention relates to a screening apparatus for treating the sewage of cities or towns so as to prevent pollution of the waters or marshes into which the sewage 15 drains. The plant in which this screening apparatus may be used should comprise drying apparatus for drying the matter removed from the sewage previous to destroying it by burning.

20 One of the objects of the present invention is to produce a screening apparatus of very simple construction which will operate effectively in practice.

Other objects of the invention will appear 25 from a thorough understanding of the invention.

The invention consists in the general combination of parts and in the simplicity of the details hereinafter described, all of 30 which contribute to produce an efficient screening apparatus.

A preferred embodiment of our invention will be particularly described in the following specification while the broad scope of 35 our invention will be pointed out in the appended claims.

In the drawings, Figure 1 is a vertical section taken through the screening chamber and illustrating diagrammatically the 40 position and arrangement therein of our screening apparatus; Fig. 2 is a horizontal sectional plan of the apparatus; Fig. 3 is a side elevation upon an enlarged scale of the screen together with its contiguous parts; 45 in this view certain parts are omitted; Fig. 4 is a vertical section taken through the side wall of the screening chamber and particularly illustrating the means for guiding the edge of the screen at this point; Fig. 5 is a side elevation of the guide bracket shown in Fig. 4, showing it in a displaced position but illustrating its relation to the screen in guiding the same; Fig. 6 is a section passing down through a part of the screen and

particularly illustrating the preferred construction for the guide rollers which may support the screen; Fig. 7 is a fragmentary view showing one of the wheels which may support and guide the screen, and illustrating the manner in which the screen runs 55 around the wheels when the apparatus is in operation; Fig. 8 is a vertical cross section taken through one of the articulations or joints in the screen and illustrating the preferred construction therefor; Fig. 9 is a 60 vertical section passing down through the parts shown in Fig. 8 and particularly illustrating means which may be employed for keeping the screen in alignment on the wheels; Fig. 10 is a plan showing a short 65 portion of the screen and illustrating the manner in which it may be built up of separate screen plates; Fig. 11 is a section taken on the line 11—11 of Fig. 10 but upon an enlarged scale, and further illustrating 70 details of the construction of the screen; Fig. 12 is a side elevation showing a portion of the screen at a joint with the parts in an inverted position; Fig. 13 is a plan showing a portion of the screen adjacent to a 75 joint; Fig. 14 is a vertical section through the screen taken on the line 14—14 of Fig. 10, and further illustrating the construction of one of the articulations or joints of the screen; Fig. 15 is a side elevation and partial section showing the preferred construction of a sprayer which may be used in connection with the screen; Fig. 16 is a front elevation showing a portion of the sprayer-head at one end thereof; Fig. 17 is a cross 80 section through the sprayer-head and particularly illustrating the means for adjusting the stream issuing therefrom; and Fig. 18 is an end elevation of the sprayer-head, the clamping bolt which holds the head in position being shown in cross section.

Referring more particularly to the parts, 1 represents a screening chamber into which the inlet 2 from the sewer leads. In the chamber adjacent to the inlet we form a 100 pocket 3 which tends to catch solid matter, and beyond this pocket a baffle or wall 4 is formed transversely and extending completely across the chamber and substantially touching the side walls 5 thereof. The sewage moves slowly from the inlet 2 and longitudinally in the chamber toward the outlet 6; in the present instance the velocity of

flow being about 60 ft. per minute. The sewage flows in a continuous stream in the chamber in the direction in which the screen is moving, and on account of the fact that the screen extends completely across the chamber it will be evident that substantially all the stream of sewage passes through the screen.

Preferably in the rear portion of the chamber beyond the wall 4, we provide a screen which is constructed in such a way that when operated it rises slowly out of the sewage and preferably in an inclined direction so that it skims the surface of the sewage and picks up solid matter carried in the sewage. We prefer to construct and arrange this screen in the form of an endless belt or screen 7, the ends of which pass around guide wheels 8 and 9, the former of which are immersed in the sewage and below the water line indicated in Fig. 1. The upper wheels 9 are at a point elevated above the water line, and when the apparatus is in operation, the screen is driven slowly, preferably by rotating the shaft 16 carrying the upper wheels 9, and the direction of rotation is that indicated by the arrows in Fig. 3.

The screen 7 is preferably formed of flat sections 11 which are connected together by joints or articulations 12. The upper run of the screen is preferably supported on guide rollers 13 preferably arranged in transverse rows, one of which rows supports the upper run of the screen directly under and opposite each of the screw conveyers. The wheels 8 and 9 may be of polygonal form and are preferably formed with means such as the sockets 14 for engaging the articulations of the screen. As illustrated in Fig. 2, we have shown four of the wheels 8 mounted on a common shaft 15 and correspondingly placed upper wheels 9 mounted on a similar shaft 16. As the lower wheels 8 rotate, there will occur a slight periodic rise of the lower portion of the screen as it runs off of the wheels 8, and this tends to produce a slight up and down vibration of the lower portion of the screen. In order to restrict this up and down vibration to the lower portion of the screen, we prefer to provide guiding means 17 at the side edges of the screen which insure that the upper portion of the screen above this point will move in a substantially straight line. This guiding means 17 may be constructed as illustrated in Fig. 4, comprising a wall bracket provided with guide rollers 18 between which the edge of the screen is received. In order to prevent solid matter getting through the space between the edge of the screen and the side walls near this point, we provide clips 19 which are preferably bent as illustrated in Fig. 1, so as to accommodate the movement of the screen and so as to "blanket" the forward side of the upper guide rollers 18.

Above the guiding means 17 we provide a simple, straight cleat 20 which is attached to the wall. These clips 19 and cleats 19^a are preferably formed of angle-iron, the flanges of which project out over the edges of the screen.

We provide means for removing solid matter from the upper face of the screen and prefer to divide this work between two transversely disposed conveyers, the lower of which is not so near the screen as the upper one. These devices are preferably in the form of two conveyer screws 20 and 21 which are mounted transversely to the screen. The periphery of the screw 20 may be within one-half inch or so of the surface of the upper run of the screen while the periphery of the upper screw 21 is very near to the screen so as to practically touch the surface thereof. Behind the conveyer screws we prefer to provide guides 22 in the form of shields, the lower portions of which may curve downwardly and forwardly so that the edges lie very near the surface of the screen. These conveyer screws are driven at a relatively high rate of speed through gear chains 23 and 24, and the conveyers are preferably of very high pitch so that they will substantially catch all material moving upwardly on the screen. However, if any material passes the screws, it will be arrested by the shields or guides 22.

In order to prevent clogging of the material at the conveyers 20 and 21, we provide means for loosening the material at this point and this preferably consists of a sprayer 25 which should extend transversely of the screen and preferably between the screws so that it may direct a jet 26 onto the screen near the screw 20. This sprayer is preferably constructed as illustrated in Fig. 15 and is preferably hung from a horizontal supply pipe 27 by means of tubular arms 28, and these tubular arms support a tubular pipe connection 29 to the ends of which curved trunks 30 are attached and between the ends of these trunks 30 a sprayer-head 31 is mounted. This sprayer-head is preferably of simple tubular form having hubs 32 which are received in the lower ends of the trunks 30. On one side the sprayer-head is provided with a longitudinal slot 33, the opening of which may be regulated by plate 34 adjustably secured in position. This sprayer-head may be clamped in any fixed adjusted position desired, preferably by means of a tie-rod 35 which passes longitudinally through the same and the ends of which pass to the exterior of the trunks 30 which have bosses 36 forming seats for the end of the tie-bolt and for the clamping nut 37. By loosening the nut 37, evidently the sprayer-head can be adjusted as desired and when the nut 37 is tightened, the sprayer-head will be securely held in its adjusted po-

sition. In order to clean the surface of the screen thoroughly beyond the conveyers, we prefer to provide a second sprayer 38 which is substantially similar to the sprayer just described. Both sprayers are supplied with water by horizontal pipe connections 39 and 40. The material which is advanced by the conveyers 20 and 21 is driven laterally toward a discharge point 41 which may be on the right side of the chamber as indicated in Fig. 2. At this point the matter is accumulated in a hopper from which it can be removed from time to time to a drier. After removal from the drier, it is burned.

The preferred construction of the screen is that illustrated in Figs. 10 and 14 inclusive. The principle on which this screen is constructed relieves the plates which form the screen of any substantial tension, at the same time permitting the formation of serviceable joints between the screen sections which permit the screen to bend as it passes around the wheels. The tension in the screen is preferably carried in two chain sections 42 between which the body of the screen lies. These chains 42 are preferably formed of long links 43 and short links 44, said short and long links being connected alternately together, the arrangement being such that the corresponding links of one chain section are connected with the corresponding links of the opposite chain sections by transverse rods 45. On account of the short links, the rods are arranged in pairs. These rods are utilized to support the sections 11 of the screen. These sections 11 are preferably in the form of plates 46, the bodies of which are provided with a great number of perforations 47, as illustrated in Fig. 13, the outline of the perforated area being indicated by the dotted line 48 in Fig. 10. The transverse edges or ends of the plates 46 are preferably formed into rolls 49 which pass around a transverse rod 45 and the longitudinal edges of the plates 46 are preferably formed of flanges 50. The flanges 50 of adjacent plates are preferably separated by bars 51, the edges of which extend below the flanges as indicated in Fig. 11. These bars 51 run upon the aforesaid rollers 13 and support the screen.

The rods 45 and the rolls 49 are preferably completely inclosed on their inner sides by means of channel-shaped shoes 53. Referring to Fig. 8 it will be seen how these shoes seat themselves in the sockets 14 of the wheels when the screen is passing around the wheels. This relieves the plates and the rods of all wear which might be due to a concentrated rubbing action which would occur if the rolls or rods came in direct contact with the sockets. It will be seen that the rolls 49 pass gradually from the round into the flat portion of the plates so that as the joints flex, the opening between the adja-

cent edges of the two plates is kept substantially closed.

From an examination of Fig. 3, it will be evident that as the wheel 9 rotates there will be a slight lateral movement of the upper run of the screen above the conveyer 21 but as the rollers 13 are also placed opposite the conveyers on the underside of the upper run of the screen they prevent any lateral movement of the screen at or below the conveyer 21. Furthermore, the wheels 9 are arranged so that the line of advance of the upper run of the screen is substantially tangent to the circumference described by the sockets of the wheel. From this arrangement the lateral movement of the screen at this point is toward the shaft 16 and away from the conveyer 21.

In order to prevent the screen from shifting laterally, we prefer to provide clips or saddles 54 illustrated in Fig. 9, which may be attached to the channel so that as the screen moves they pass near the edges of the wheels and engage with the edges thereof to prevent the shifting referred to.

The rollers 13 are preferably constructed as illustrated in Fig. 6. Each roller consists of a cylindrical shell 55 having a central fin 56 which runs in a peripheral groove formed between two fixed disks 57 clamped to a fixed arbor 59.

Special attention is called to the advantage of admitting the spraying water by means of two inlets 28 instead of a single inlet. If a single inlet were used taking the supply coming from two directions, the velocities developed in the water coming from opposite directions would greatly reduce the velocity of flow in the sprayer. In our case, if desired, the connection 27^a between the tubes 28 could be closed but in any event this part of the device would be filled with "dead" water and a similar effect would result in the pipe connection 29^a of the connection 29 so that a good velocity of flow results in the trunks 30.

On account of the polygonal form of the guide wheels or pulleys 9, it will be evident that the upper portion of the screen above the screw conveyer 21 will rise and fall slightly as the wheels 9 rotate. However, the rollers 13 directly under the screw conveyer 21 support the screen and prevent its moving away from the screw conveyer. The distance of the screw conveyer 21 and its adjacent rollers 13 is sufficient to insure that there will always be one or more joints between the pulley and the screw conveyer, which insures that this up-and-down movement can occur without injury to any of the parts.

It is understood that the embodiment of the invention described above is only one of the many forms the invention may take, and we do not wish to be limited in our

invention nor in the scope of our claims to the particular construction described above.

What we claim is:—

- 5 1. In a sewage screening apparatus, in combination, a screen, means for guiding and advancing the same in a direction inclined with respect to the water level of the sewage, a transverse row of rollers engaging the under side of the upper run of the screen for supporting the same, and a screw conveyer disposed transversely to said screen above the upper run thereof, and opposite to said supporting rollers for advancing material gathered on said screen in a lateral direction to remove the same from the screen.
- 10 2. In a sewage screening apparatus, in combination, a screen, means for guiding and advancing the same in a direction inclined with respect to the water level of the sewage, a transverse row of rollers engaging the under side of the upper run of the screen for supporting the same, a screw conveyer disposed transversely to said screen above the upper run thereof and opposite to said supporting rollers for advancing material gathered on said screen in a lateral direction to remove the same from the screen, and a sprayer extending transversely of the screen for directing a spray onto the screen adjacent said screw conveyer.
- 15 3. In a sewage screening apparatus, in combination, a screen, means for guiding and advancing the same in a direction inclined with respect to the water level of the sewage, a transverse row of rollers engaging the under side of the upper run of the screen for supporting the same, a screw conveyer disposed transversely to said screen above the upper run thereof and opposite to said supporting rollers for advancing material gathered on said screen in a lateral direction to remove the same from the screen, a sprayer extending transversely of the screen for directing a spray onto the screen adjacent said screw conveyer, and a shield over and adjacent the said upper run of said screen and between said sprayer and said screw conveyer.
- 20 4. In a sewage screening apparatus in combination, a pair of endless chains comprising links, transverse rods connecting links at one of said chains to the corresponding links of the other of said chains, wheels having sockets receiving said rods to drive said chains and screen sections supported between said rods, said screen sections hav-

ing rolls passing around said rods and channel shoes enveloping said rods and said rolls and received in said sockets.

5. In a sewage screening apparatus in combination, a pair of endless chains comprising links, transverse rods connecting links in one of said chains to the corresponding links of the other of said chains, wheels having sockets receiving said rods to drive said chains, screen sections supported between said rods, and channels receiving said rods and adapted to seat in said sockets when said wheels drive said chains.

6. In a sewage screening apparatus in combination, a screen disposed in an inclined position and adapted to raise solid matter from the sewage, said screen being in the form of an endless belt, wheels over which said screen passes, and means for guiding the middle portion of the screen in a substantially straight line and permitting a lateral movement of the lower portion of said screen as the same unrolls from the wheels.

7. In a sewage screening apparatus in combination, a screen disposed in an inclined position and adapted to raise solid matter from the sewage, said screen being in the form of an endless belt, wheels over which said screen passes, means for guiding a portion of the screen in a substantially straight line and permitting a lateral movement of the lower portion of said screen as the same unrolls from the wheels, said guiding means consisting of rollers disposed above and below said screen, and means projecting over said rollers and projecting over the laterally movable portion of said screen at the edge thereof.

8. In a sewage screening apparatus, in combination, an endless screen composed of a plurality of hingedly connected plates, said screen disposed in an inclined position, means for driving the same in a direction to elevate solid material carried in the sewage, means for supporting the upper run of said screen on the under side of said upper run, and a screw conveyer disposed opposite to said supporting means for engaging the sewage on the screen and for advancing the same laterally off of the screen.

Signed at New York city, N. Y., this 31 day of January 1913.

ALPHONSE M. LEONI.
ALBERT F. SCHREINER.
